UNITED STATES PATENT OFFICE.

ANGELO PERRI, OF GROVELAND, MASSACHUSETTS, ASSIGNOR TO REECE SHOE MACHINERY COMPANY, OF BOSTON, MASSACHUSETTS, A CORPORATION OF MAINE.

LASTING-MACHINE.

1,222,126.

Specification of Letters Patent. Patented Apr. 10, 1917.

Application filed May 11, 1916. Serial No. 96,748.

To all whom it may concern:

Be it known that I, ANGELO PERRI, a citizen of the United States, residing at Groveland, in the county of Essex and State of Massachusetts, have invented certain new and useful Improvements in Lasting-Machines, of which the following is a specification, reference being had therein to the accompanying drawing.

10 This invention relates to "lasting machines", and more particularly to a novel shoe holding device or "jack" and to "wiping mechanism" coöperating therewith.

15 In the lasting of shoes a sectional wooden "last" is usually employed for giving form to the shoe. The shoe upper is required to be assembled with the sole about the last, as a form, and the lasting process may comprise the steps of first "pulling-over" the 20 flexible upper about the fore part of the shoe and thereafter "wiping" the extending side margins, and the margins at the heel and toe. Such wiping consists in forcing, smoothing and pressing the overhanging material of the upper into place about the last and sole, where it may be suitably secured 25 preparatory to subsequent operations including attachment of sole and upper. In my prior Patent No. 1,168,963, granted January 30 18th, 1916, I have shown a machine in which all of the above described steps or operations may be performed, the machine comprising a shiftable jack which holds the 35 shoe, a pulling-over mechanism, and heel and toe wiping mechanisms.

The present invention in its entirety involves not merely the construction of jack herein disclosed, and the novel features thereof *per se*, but also wiping mechanisms 40 for the toe end and the heel end, respectively, of shoes, possessing certain characteristic features giving advantageous coöperation with features of such jack; and the principal object of the present improvement 45 is to afford a shoe holding jack and a lasting machine including the same, which will be simple and durable in construction and of maximum efficiency and convenience in operation.

50 The present application, therefore, discloses one form or illustration of a shoe holding jack and of a lasting machine including

the same, embodying features of the present invention. The novel jack may be variously employed, but, as herein disclosed, is more especially designed to be employed in a so-called "bed lasting" machine, in which the inverted shoe is inserted after having been pulled over, and in which usually both the heel and toe portions of the shoe upper are wiped and secured.

The toe wiping mechanism and the heel wiping mechanism which I prefer to employ in cooperation with the shoe holding jack hereof are herein sufficiently illustrated to give a complete understanding of the relation of such mechanisms to the jack and to each other. However, the toe wiping mechanism is not herein shown in complete detail, and neither is the heel wiping mechanism, as these are the subjects of separate patent applications, to which reference should be made for further details. The toe wiping mechanism is completely illustrated and explained in my copending application Serial No. 83,540, filed March 11, 1916, and the heel wiping mechanism in copending application Serial No. 97,516, filed May 15, 1916.

Indeed, the shoe holding jack, toe wiping mechanism and heel wiping mechanism are in reality combined as a single machine, and therefore the three patents may for convenience be considered in conjunction with each other.

Among the particular objects to which the present invention is directed is to provide a lasting machine including a shoe holding jack, which machine is adapted to efficient and convenient use for the wiping of both 90 shoes, that is, the right and left shoes of a pair. A machine which may be quickly changed over for this purpose is very advantageous in permitting both shoes of a pair to be completed before operating on 95 other shoes.

Another object is to provide the combination with lasting means of a jack adapted to hold right and left shoes of various shapes, styles and sizes with the apex-line, that is, 100 the line joining the apexes of the toe and heel of the shoe always standing in the same longitudinal direction, this being preferably accomplished herein by a transverse swing-

ing of the jack, avoiding any bodily transverse shifting of wiping mechanism.

It is another object hereof to provide a lasting machine wherein the wiping mechanism may be bodily swung, subsequent and independent to the adjustment of the jack, and substantially about the apex of the shoe contour at one end as a center, in order to set the line of wiping action into proper relation or coincidence with the center line of the shoe at that end.

It is another object hereof to provide a shoe holding jack which may be adjustably swung substantially about the apex of the heel to bring the apex of the shoe toe into longitudinal alinement with the heel apex, in combination with coöperatively adjustable heel and toe wiping mechanisms.

Another object is to provide a jack for a lasting machine, which, including the heel rest and the toe rest and the hold-down, may be bodily swung about a given center or axis. Another object is to provide a jack which may be so swung as a unit and is provided with relatively movable heel and toe supports adapted to receive shoes of varying sizes.

Another object is to provide a jack, which, by the action of removing a shoe and inserting its mate, automatically symmetrically reverses the position of the jack or otherwise adapts it to the lasting of the mate. Another object is to provide for alternately locking the jack in its two positions in which right and left shoes are to be lasted.

Another object is to provide a lasting machine wherein the readjustment of the jack, whether automatic or otherwise, for rights and lefts performs an automatic adjustment upon the wiping mechanism to coöperate therewith; particularly that the lateral swinging of the jack will reset the line of action of the heel wiping mechanism so as to lie in a line coincident with the center line of the heel part of the shoe.

Another object is to provide for the shoe holding jack a hold-down of extremely simple and effective construction and the use of which dispenses with the usual abutment at one end of the shoe, while wiping the other end.

To the attainment of the above referred to objects and advantages the present invention consists in the novel lasting machine or wiping mechanism, and the novel features of arrangement, design, combinations and detail herein illustrated or described and claimed.

60 The accompanying five sheets of drawings contain the following figures.

Figure 1 is what may be considered a general front elevation of a lasting machine comprising a shoe holding jack and toe and heel wiping mechanisms illustrating one

form or embodiment of the present invention. This view corresponds with Fig. 13 of application 83,540 and with Fig. 1 of application 97,516.

Fig. 2 shows in detail a portion of the 70 pedal connections, taken on the plane 2—2 of Fig. 1.

Fig. 3 is a top plan view of the entire mechanism shown in Fig. 1, the parts set for lasting a right shoe.

Fig. 4, on a larger scale and omitting all details, indicates in top plan view the re-adjusted positions of the parts for operation upon a left shoe.

Fig. 5 on a still larger scale shows in top 80 plan view the shoe holding jack, the shoe being omitted but its position indicated by dotted lines, and sufficient of the heel wiping mechanism being illustrated to indicate certain features of co-action.

Fig. 6 is a front elevation of the parts shown in Fig. 5.

Fig. 7 is a partial right elevation and section taken on the plane 7—7 of Fig. 6.

Fig. 8 is a partial right elevation and section taken on the plane 8—8 of Fig. 6.

Fig. 9 is a partial top plan view and section on the plane 9—9 of Fig. 6.

Fig. 10 is a right elevation better showing the relation of certain parts in Fig. 8.

Fig. 11 is a diagram to assist explanation of the mode of readjustment of the jack and wiping mechanism to allow for changes in the degree of curvature or straightness of shoes.

Generally speaking, a bed lasting machine such as that indicated herein may comprise a base 19, upon which are supported the jack or shoe holding mechanism 21, and to the right of the jack the heel wiping mechanism 22, and to the left of the jack the toe wiping mechanism 20.

Since the novelty hereof is not restricted to the construction of the jack mechanism 21, but resides also in the toe and heel wiping mechanisms 20 and 22, it will be necessary to describe the three mechanisms. The wiping mechanisms, however, being completely described in my copending applications, need not be so fully described herein. 110 It will be convenient to first describe generally the toe wiping mechanism, and subsequently the jack and the heel wiping mechanisms. The same reference numerals will be employed for all three patents.

Referring first to the toe wiping mechanism 28, the description in said application 83,540 may conveniently be condensed as follows.

At the left of the bed is an elevatable support 23, which may be lifted and lowered by a pedal 24 during wiping operations. Sliding on the support 23 is a carriage 25, which may be shifted toward and from the shoe by a hand-wheel 26 acting through a 130

threaded lug 27 depending from the carriage. Upstanding from the carriage are brackets 30, which at their upper ends give support to the toe wiping mechanism or 5 "head". At the extreme right of the toe wiping head are seen the wiper plates 60, 61.

The movements and adjustments of the toe wiping mechanism are various. In addition to the longitudinal adjustment toward and from the shoe by the hand-wheel 26 and the lifting and lowering movements by the pedal 24, the toe wiping head is capable of being bodily tilted longitudinally 10 to different degrees from the horizontal, for example, as indicated in Fig. 1. This tilting is permitted by trunnion bearings 31 at the top of the brackets 30, these giving support at diametrically opposite points to an upright bearing ring 32 carrying the wiping mechanism. The ring 32 may be tilted from the vertical by suitable connections from a hand-wheel 36. Also the wiper plates are designed to have operative movements 15 toward and from the shoe, the advance of the plates being accompanied by a convergence thereof and their retreat by a swinging apart or divergence thereof. Another movement or adjustment, and one 20 which is characteristic of this toe wiping mechanism, is a movement of inversion, by which the single set of wiper plates is adapted from one shoe to the other, the inversion insuring symmetry of contour. The 25 advancing and retreating wiper devices are so arranged as to be adjustable to various inclines from the longitudinal axis of the machine. This is necessary from the fact that shoes are seldom straight, and the center line of the shoe forepart extends at various inclines from the center line of the rear part. This adjustment is performed in a 30 characteristic way, the swing of the mechanism taking place about a center substantially coinciding with the tip or apex of the 35 contour of the wiper plates. The mechanisms for performing these last two mentioned adjustments are so combined and harmonized that the inversion of the wiper 40 plates to reverse them in changing from one shoe to another simultaneously and symmetrically reverses the direction or incline of wiping action. Another adjustment is a lateral tilting to accord with variations in 45 shoes, but this requires no particular reference in the present patent. A hand-wheel 145 may be turned for varying the lateral tilt. All parts of the machine are constructed, combined and adapted to enable 50 the quick and ready change-over required to enable the successive wiping of rights and lefts, thus obviating the practical disadvantages of lasting first a number of rights and then a number of lefts, as explained in application 83,540. 55

The inverting operation referred to, which symmetrically effects a reversing of the contour and the incline of action of the lateral tilt of the wiper plates, is permitted by bodily mounting the wiper plates and 60 their supporting devices within a rotatable shell or flanged ring 34, engaged within the upright bearing ring 32. The actual revolving of the shell 34 may be accomplished by a rightwardly projecting handle 130. 65 Suitable stop devices or lugs serve to properly position the revoluble shell when the inverting operation is performed. A lever 150 is connected to cause the unlocking of the shell when desired to invert it by the 70 handle 130. 75

The change of incline of wiping action is effected by mounting the wiper plates and their supporting devices upon a laterally shifting carriage 45, which engages with 80 arc-shaped tracks 43 secured to the shell 34, the carriage having special correspondingly shaped ribs 47 for this purpose. As indicated in Fig. 4, the arc-shaped guides and ribs are struck about the center F, 85 which is the apex of the contour of the wiper plates. The adjustment may be actually effected by hand-wheel 120 and suitable connections, which serve to throw the carriage 45 toward or from a true longitudinal position to the degree required by 90 the particular shoes being lasted. 95

In order to permit the advancing and retreating movements of the wiper plates 60, 61, the latter are supported at the forward end of a longitudinally sliding carrier 50, mounted at the center of the wiping head or with its axis coincident with the axis of the transversely sliding carriage 45. The carrier 50 is a generally cylindrical member, but is splined within the circular part of the carriage 45 so as to partake of any revolution imparted to the carriage through the surrounding revoluble shell. The wiper plates 60, 61 are at the righthand or forward end of the carrier 50, and the carrier 100 is caused to move longitudinally by connections at its opposite or left end. 105

As will be clear from Fig. 1, the parts supported by the carrier 50 are symmetrical, 115 so that the wiping mechanism may be operated in either of two positions, one inverted with respect to the other. As indicated in Figs. 1, 3 and 4, the carrier 50 is laterally enlarged in the form of wings 54, 120 and forward of this point it is designed to accommodate the wiper plates 60, 61 and associated parts. 125

The swinging toward each other or converging of the wiper plates during their operative or advancing movement may be effected in various ways, for example, as illustrated in said application 83,540, in which the two plates simultaneously swing about their point of juncture, which is the 130

same center F about which adjustment is effected for incline of direction of wiping action. A toothed bracket 73 is one of the elements of the mechanism for swinging the 5 plates.

Both above and below the wiper plates are blocks 80, which assist in the wiping operation. The blocks which are above the wiping plane stand between the plates and 10 the abutments or cover pieces 75 and give rigid reinforcement during the wiping operations. The blocks 80 which at any time are beneath the wiping plane are capable of yielding, so that contact with the shoe 15 will repress the blocks, and the blocks are made to serve as gages by predetermining their extent of yield. In order to render the underneath blocks yieldable and the upper ones unyielding, a vertically sliding lock device or bar 90 may be used. This requires 20 to be lifted whenever the wiping head is inverted.

The controller or instrument for manipulating the wiper plates may be in the form 25 of an operating lever 100, located convenient for the lefthand and supported by a bracket mounted on the bearing ring 32. The wiping lever 100 extends forwardly and swings rightward and leftward. The lever 30 is provided with a latch 103 for locking it and the wiper plates in their advanced positions. The movements of the actuating lever are communicated to the carrier 50 by means of a downwardly extending telescopic rod 107. The connections between 35 the lever and the carrier, including the rod 107, are such as to freely permit the previously recited adjustments of longitudinal and lateral tilt, as well as the bodily in- 40 version of the wiping head.

Coming now to the jack mechanism 21, this, as already explained, comprises shoe supporting devices permitting the shoe A to be swung horizontally about a vertical 45 axis or center located at D near or approximately at the tip of the heel. This permits the forepart of the jack to be swung toward and from the operator, or transversely to the longitudinal axis of the machine in 50 adapting it and the shoe to the toe wiping mechanism. It has been explained that the adjustment of the angle of action of the toe wiping mechanism is performed about the point or center F as an axis, F being the 55 apex of the contour of the toe wiper plates. This point, of course, advances and retreats during the wiping movements. When the plates have been brought up into contact and conformation with the toe of the shoe, 60 the apex F of the plates will coincide with the apex of the shoe toe, which latter may be designated F'. Since the bodily adjustment of the toe wiping mechanism toward and from the shoe is strictly longitudinal 65 in direction, it follows that the point F, and

therefore the point F', when the plates are in position to conform with the shoe, will always be in the same longitudinal axis, plane or line. It is my preferred plan that the shoe apex F' shall be in the same longitudinal axis as the center D about which the jack swings. In other words, every shoe, straight or crooked, right or left, placed in this machine will be so located that the line F'-D joining the apexes of the toe and 70 heel will be constant in location and direction. 75

The diagram, Fig. 11, indicates these relations of the parts. This diagram indicates in full lines a left shoe of decided curvature 80 and in dotted lines a more nearly straight left shoe. The longitudinal axis H-H of the machine is constant for all shapes of shoes and for rights and lefts. The centers or apexes D and F' are both in this axis 85 when wiping. In order to bring the shoe into the position indicated, the jack will be swung about the center D until the shoe toe apex F' lies in the longitudinal axis H-H. This is indicated by the coincidence of the 90 wiper plate apex F and the shoe toe apex F'. In this lateral swinging of the jack for rights and lefts and for different shapes and styles of shoes, the jack assumes different positions, which may be indicated by laying 95 out the axis of the jack itself. This axis will seldom coincide with the longitudinal axis H-H. Thus, in the supposed instance the forepart of the jack has been swung out into the direction D-J, which represents 100 the axis of the jack for the left shoe A. With the jack lying in the position D-J and the apex of the shoe toe at F' on the longitudinal axis, the toe wiping mechanism will now be adjusted so that its angle of 105 action will lie along the line K-F'. This adjustment is in effect performed by swinging about the apex F'. This adjustment, therefore, is readily made, so that the wiper plate contour will conform with the shoe 110 toe and so that the angle of action K-F' will substantially coincide with the center line of the forepart of the shoe, as indicated.

The readjustment for a right shoe which is the mate of the left shoe A shown in full lines, it is understood, would be easily effected by a more symmetrical shifting of the points J and K across the axis H-H. In other words, it is merely necessary to invert the wiping mechanism, which, as explained, reverses the angle of action, and to swing the jack forwardly until its axis is forward of the longitudinal axis by the same extent that the jack axis D-J is indicated 115 to the rear thereof.

When, however, a decided change in the shoe style is made and a comparatively straighter shoe A' is substituted, as shown in dotted lines, the readjustments will not be symmetrical. The more nearly straight 120 130

the shoe, the more nearly will the jack axis approach the longitudinal axis. Therefore, the first readjustment is to swing the jack axis from D—J to D—J'. This is such as to bring the apex of the shoe toe to the same point F' on the longitudinal axis. The angle of action of the toe wiper plates will be correspondingly adjusted, as indicated at K'—F', which is the new center line of the 10 forepart of the shoe.

The structure of the jack mechanism is best shown in the partly sectioned front view, Fig. 6, in connection with the top view, Fig. 5, additional details being shown 15 in Figs. 1, 2, 7, 8 and 9. The jack comprises a toe rest 155 and heel rest 156, both supported on a jack base plate 157 of generally square form, located above the top plate or bed of the base 20 of the machine. The jack base 20 plate 157 is movable over the bed by swinging about a center or vertical axis D, located substantially beneath the tip or apex of the heel of a shoe or last held on the jack. As 25 will appear, the heel rest is adjustable toward and from the toe rest. Also, the jack base plate carries a hold-down, which clamps a shoe in position upon the toe and heel rests.

This entire jack mechanism is bodily shift-30 able, the jack base plate for this purpose being secured to a vertical shaft 158. The toe end of the jack base plate is provided with anti-friction rollers 159 running upon a machined portion of the bed. Before de-35 scribing the swinging movements of the jack and the preferred mode of effecting them, it will be convenient to describe the toe and heel rests and the hold-down, all of which swing bodily with base plate 157 about ful-40 crum shaft 158.

The toe rest 155 may for convenience comprise a resilient pad 160 pivotally mounted at the top of an upstanding bracket 161 bolted to the swinging end of the jack base 45 plate. The vertical portion of the bracket 161 serves as a guide for a portion of the hold-down or shoe clamping mechanism.

The heel rest 156 consists of an upstanding member of solid construction, its base 50 162 being solidly, but slidably, mounted in the jack base plate. The upper end of the heel rest is socketed in a usual manner to hold interchangeable pins 163. These pins are non-cylindrical where they fit into the 55 heel rest socket, but above the heel rest are cylindrical and are of varying heights and slants, so that, when the socket in the shoe last is fitted upon the appropriate pin, the shoe will stand at the correct height and 60 angle, so that its forepart will rest snugly upon the pad of the toe rest 155.

As seen in Figs. 5 and 8, the upper side of the jack base plate is not merely recessed longitudinally to accommodate the 65 slidible heel rest base 162, but is undercut

to receive rollers 164 extending transversely from both ends of the sliding heel rest base. This arrangement gives a very firm connection, and at the same time permits the heel rest to be longitudinally slid with 70 facility.

The purpose of the sliding of the heel rest is to permit relative approach and separation of the toe and heel rests to accommodate the jack to varying shoes and, as indicated, 75 I prefer that the heel rest be the one that moves toward and from the other. When the shoe has been properly set on the heel rest, the operator merely pushes the shoe and heel rest toward the toe rest until the shoe 80 toe snugly rests on the latter. Before the wiping process commences, the heel rest is locked in its position. For this purpose the interior of the jack base plate is transversely toothed at 165 to receive a dog 166, which is 85 pivotally mounted on the heel rest to engage and disengage the teeth 165. A spring 167 tends to lift the dog and at the proper time the dog is pressed down into engagement with the teeth by a bunter 168. This for 90 convenience is a spring-pressed device mounted on the hold-down mechanism, so that, when the latter is depressed to clamp the shoe in place, the heel rest becomes automatically locked in position.

The mechanism for clamping or holding the shoe down upon the toe and heel rests is best shown in Figs. 6 and 7, and in top view in Fig. 5. This mechanism is fitted and operated from beneath the shoe so as to stand 95 out of the way when inserting and removing the shoe. The members which hold the shoe or press its sole downward are, therefore, in the form of hooks 170, there being one at each side, and these being applied to the shoe 100 at a point between the toe and heel rests, but preferably at the ball of the shoe or near the toe rest. As seen in Fig. 7, the hold-down hooks 170 are adapted to be swung inward toward each other over the shoe and to be 105 pulled down into clamping position.

Convenient mountings for the hold-down hooks and the connections for causing them to swing together and descend in clamping a shoe, and vice versa in unclamping it, will 110 now be described. The operations are controlled by a pedal 185, the connections to which will subsequently be explained.

The hold-down hooks 170 are in the form of upwardly extending arms pivoted respectively to the front and rear sides of an equalizing lever 177 centrally pivoted upon a T-shaped slide 171, which, as plainly seen in Fig. 6, is capable of moving up and down, with the vertical portion of the toe rest bracket 161 as a guide. A spring 172 is arranged to pull the hold-down hooks toward each other, excepting when the hooks are forced apart in the manner subsequently to be described. The dotted lines in the up- 120 125 130

per part of Fig. 7 indicate not only the extent of swinging of the hold-down hooks, but also the extent of vertical movement of their pivots and of the slide 171 carrying the same. 5 Each hooked arm 170 is provided near its pivot with a shoulder or contact surface 173 adapted to be pressed upwardly for the purpose of separating the hold-down hooks against the tension of spring 172. For effecting the in and out swinging movements of the hold-down hooks, and also the up and down movements of the slide 171 carrying the same, I have provided the following simple mechanism. This comprises an actuating bar 174 connected to and extending downwardly from the slide 171. This bar is adapted to be pulled down and moved upwardly under control of a pedal 185. The bar has a block and slot connection with the 10 slide, permitting a limited relative movement. Thus, a lug 175 is formed on the slide 171, this acting as a block and engaging in a vertical slot formed in bar 174 at 176. The parts are secured in alinement by 15 the equalizing lever 177 pivoted to the block 175. The upper end of the actuating bar 174 has transversely extending contact arms 178 located immediately beneath and adapted to contact the shoulders 173 of the hold-down arms. This coöperation is effected by 20 the relative movement between the slide and bar permitted by the play of the block 175 of the former in the slot 176 of the latter.

When the actuating bar 174 is lifted, its 25 contact arms 178 come up against the shoulders 173 of the hold-down arms, and the continued lifting movement serves to bodily lift the hold-down arms and the slide 171 carrying them, the spring 172 being strong enough 30 at this time to resist the separation of the arms. After a suitable lifting of the hold-down hooks in this way, the slide 171 comes in contact with a stop pin 179 mounted on the guide or bracket 161. This halts the 35 lifting of the slide, and the continued rising of the bar thereafter forces the hold-down hooks and arms apart, until, when the upward movement of the bar is stopped by the block and slot connection 175—176, the hold-down hooks assume the dotted position 40 shown in Fig. 7. The descending movement of the actuating bar causes exactly the reverse operation, the hold-down hooks first swinging toward each other, so as to overhang the shoe, and then descending, the 45 pedal finally pulling forcibly down and the parts becoming locked in the final position.

Before describing the pedal connections, I 50 will mention a device for locking the jack mechanism against accidental transverse swinging. It has been explained that the jack base plate 157 may swing transversely at the toe end about the vertical fulcrum shaft 158 as an axis, this shaft correspond- 55 ing in position with the axis D, heretofore

referred to. It has also been explained that in changing from a right to a left shoe, and sometimes in changing from one style to another, a shifting of the axis of the jack is necessitated, this being accomplished by 60 the swinging referred to. After the shoe has been placed upon the heel and toe rests and before the hold-down is applied, the proper adjustment of the jack is effected. The toe end of the jack swings transversely 65 while the rollers 159 travel over the bed.

To the rear of the rollers 159 the bed is provided with upstanding teeth 180 in the form of a curved rack concentric with the swinging movements of the jack. Above 70 the rack 180 the jack base plate at each side is provided with a spring lifted dog 181. These dogs are adapted to be forced downwardly to engage with the teeth 180 to lock the jack against transverse movement. This 75 is effected automatically when applying the hold-down. The actuating bar 174 is provided at front and rear with spring bunters 182.

The bunters 182 are similar to the bunter 80 168, previously mentioned. All of them are mounted on the descending actuator bar 174, and serve on the forcible descent of the bar to effect their respective locking functions. For convenience the bunter 168 is omitted 85 from Fig. 7, although its bearing lugs are indicated. Each bunter includes a powerful spring which permits its yielding, so as to prevent breakage, the spring being sufficiently strong to overpower the 90 comparatively light springs tending to withdraw the dogs 166 and 181, respectively, from the teeth 165 and 180, respectively.

When the actuating bar 174 is pulled 95 downwardly the bunter 168 with its strong 100 spring is caused to press resiliently upon the dog 166, the light spring of which yields so that the dog is pressed into contact with the toothed device 165 below. At the same time the bunter 182 analogously presses the 105 dog 181 downwardly into engagement with its toothed device 180. Thus the heel support is locked against longitudinal movement and the jack is locked against the 110 swinging.

The descent of the actuating bar 174, therefore, not merely swings the hold-down hooks together and applies them on top of the shoe to clamp it upon the shoe rests, but also at the same time automatically locks the heel 120 rest and the jack base plate against accidental movement.

The connections from the pedal 185 for pulling down the actuating bar 174 and effecting the described operations may conveniently be as follows. The pedal, as seen in Fig. 2, extends forwardly from a rear fulcrum, and at an intermediate point is connected by a pair of compensating links 125 186 with a horizontal lever 187 fulcrumed, 130

as seen in Fig. 1, at its righthand end, and provided at its left end with a spring 188 tending to lift it and the pedal. Near the free end of the lever is an upwardly extending rod 189, to which is pivoted a slotted head 190. The head 190 is guided to slide vertically, having for this purpose recessed cross arms 191 engaging opposite vertical guide rods 192, as seen in Figs. 6 and 9. The 5 circularly flanged lower end of the actuating bar 174 rests directly on top of the cross-head 190, and the two are so connected that the pedal movements effect the lifting and falling of the bar, while permitting transverse movements of the bar during adjustments of the jack mechanism across the bed of the machine. The slot at 193 in the cross-head is curved, being an arc struck about the axis D as a center. A pin or bolt-like extension of the actuator bar passes downwardly through the slot 193, and below, as seen in Fig. 7, is provided with a head or stop in the form of check nuts 194. The 10 check nuts are so placed as to produce a running fit, so that the check nuts easily move transversely during any adjustments of the jack.

With the above described connections, the depression of the pedal 185 operates through 15 the lever 187 and bar 174 to move the hold-down hooks over the shoe, depress them into place and lock the heel rest and jack base plate against movement. The pedal and bar are themselves adapted to be locked in 20 this position, so that the operator is relieved from holding down the pedal during the wiping operations, the other pedal 24 requiring to be actuated by him in lasting the shoe toe. For this purpose the pedal 185 25 is provided with a toothed rack 195 adapted to be engaged by an elongated pawl 196, constituting the lower end of a spring pressed lock lever, the upper end 197 of which is shaped to constitute a convenient 30 handle for effecting the release of the pedal when the shoe is to be unclamped.

The jack base plate 157 and the entire jack mechanism carried with it may be shifted transversely for rights and lefts 35 either by hand or automatically. In either case I prefer to provide symmetrical stops to properly limit the swinging movement, and, by rendering these stops adjustable at will, the angle of the jack may be altered in 40 different degrees to suit different styles of shoes.

For these purposes a pair of symmetrically opposite stops 200 may be employed, as seen in Figs. 8 and 5, these being located 45 at a point suitably removed from the axis D of swinging, for example, somewhat to the right of the axis. The jack base plate 157 is indicated as being apertured to afford shoulders or stop contacts 201. Fig. 8 shows the 50 jack centrally located, and therefore in con-

tact with neither stop 200. When swung to either side, one of the stops will be met, and the displacement to one side will necessarily be symmetrical to the opposite displacement.

70

To permit increasing or decreasing the swinging displacement of the jack, the stops 200 are movably mounted to approach and recede from each other transversely to the machine. They are both guided and actuated for this movement by means of an adjusting shaft 202, having right and left screw-threaded portions engaging threaded recesses in the respective stops, so that, when the shaft is turned by the hand-wheel 203, 75 the stops are moved together or apart.

75

It should be observed that moving the stops apart decreases the latitude for shifting of the jack. Therefore, to increase the angularity of the jack for a very curved 80 shoe, the hand-wheel 203 should be so turned as to cause the stops to approach each other to the proper extent. If the stops be thrown apart as far as permitted by the space between the contact shoulders 201, obviously 85 this would centralize the jack and hold it against any lateral movement.

85

I prefer that, when the pedal 185 is operated to unclamp one shoe and to clamp the next one, this rising and falling movement of the pedal will, without any further attention from the operator, effect the symmetrical reversal of the position of the jack, throwing it from one incline with respect to the longitudinal axis of the machine suitable 90 for a right shoe to an opposite incline suitable for the left shoe, and vice versa. For this purpose the fulcrum shaft 158, about which the jack swings, is constructed to extend downward to where it may be employed 95 as a rock shaft to be rocked by a suitable cam and stud arrangement under the control of the pedal, to throw the jack alternately rearward and frontward.

100

Referring to Fig. 6, the jack fulcrum 110 shaft 158 is shown as provided with a sleeve 205 having a leftward extending rock arm and roll 206. The sleeve 205 is connected to the shaft by a spline 207, so that, when the cam roll 206 is actuated, the shaft, and 115 therefore the jack, are swung bodily, while up and down sleeve adjustments are permitted.

115

In order to throw the cam roll 206 first one way and then the other to alternately 120 swing the jack from side to side whenever one shoe is changed for another, I may employ a cam or wedge device 208. This stands below the roll, and, as seen in Fig. 10, is capable of assuming either of two positions, 125 in one of which it will throw the roll forwardly and in the other rearwardly. The wedge cam for convenience is the shape of an arrowhead, having the inclined cam faces, beneath which are shoulders, and there being 130

a shank 209 extending downwardly to where its lower end is pivotally mounted on a rising and falling block or head 210. The block is recessed, as shown, so that the walls 5 of the recess constitute abutments for the wedge cam shank in one or the other position.

The lifting and depressing of the block 210 carrying the wedge or cam 208 is seen 10 in Figs. 1 and 6 to be effected by a rod 211, pivotally connected above and below to the block 210 and the lever 187, which rises and falls with the pedal 185 and the hold-down mechanism.

15 The wedge cam 208 could be thrown by hand from one position to the other. Whenever it is thrown, it results that the next lifting movement of the block 210 will cause the cam to act upon the roll 206 to reverse 20 the jack position. The wedge cam might be thrown before the lasting of every shoe, so as to permit the lasting of first one right shoe, and then one left shoe, and so on; or it might be thrown for every second operation, so that, after a left and right shoe have 25 been lasted, the next pair could be lasted first right and then left, and the third pair first left and then right, and so forth.

Obviously the degree of throw of the jack 30 caused by the coöperation of the wedge cam 208 with the roll 206 will be constant in amount unless some means of adjustment or a yielding element be interposed. Without either, the cam might tend to throw the jack 35 farther than permitted by the adjustable stops 200, before mentioned. I have provided means for adjusting the action of the cam 208 to conform with the adjustment of the jack stops 200. Referring to Figs. 6 40 and 8, an enlargement or block 212 is shown formed or securely fixed upon the lower end of the fulcrum shaft 158. This block, and also the sleeve 205 above it, are provided with bosses which are in alinement. An adjusting shaft 213 extends through both 45 bosses and is threaded where it engages the threaded interior of the boss on sleeve 205. A simple pin and groove device prevents vertical movement through the other boss. 50 When the hand-wheel 214 upon the adjusting shaft 213 is turned, the sleeve 205 is lifted or lowered. In this way the height of the cam roll 206 is adjusted at will. Since the upward and downward movement of the 55 wedge cam 208 is fixed in extent, it is clear from Fig. 10 that an alteration in the height of the cam roll will vary the action of the cam. The higher the cam roll is adjusted, the less effect the cam will have in throwing 60 the jack to one side or the other.

It follows that, when the hand-wheel 203 is turned for throwing the jack stops 200 toward each other to permit increased swing of jack, the hand-wheel 214 should be turned 65 to lower the cam roll 206, so that the wedge

cam will have a correspondingly increased effect.

It has been above explained that the wedge cam 208 might be thrown or tilted to its reversed position prior to the lasting of each individual shoe, or less frequently. I have shown automatic means for relieving the operator from attention to this detail by shifting the wedge cam to its opposite position with each operation of the hold-down mechanism performed upon the change of shoes. 70 75

The wedge cam is a very light member and capable of being thrown across by a light blow beneath the shoulder at the side 80 toward which the cam is tilted. To give such a light blow at one side or the other, a pair of light spring fingers 215 are provided, so located that on the depression of the pedal 185 and after the wedge cam has disengaged 85 the cam roll, the lower side of the wedge cam is caused to strike against the spring finger 215 at that side, thus causing the light blow necessary to tilt the cam across to the other side. 90

For convenience the spring fingers are mounted on the block 212, which is fixed at the lower end of the fulcrum shaft 158. Moreover, by this arrangement, as will be clear from Fig. 9, the spring finger which is 95 to be operative, will stand properly beneath the wedge cam, while the other spring finger will be swung outwardly so as to be inoperative.

The heel wiping mechanism, which is explained more in detail in said application No. 97,516, is sufficiently shown for the purpose hereof in Figs. 1, 3, 4, 5, and 6, and may be partly described as follows. 100

At the right end of the machine base is a 105 rising and falling support 218 similar to the support 23, which carries the toe wiping mechanism up and down. The support 218 is lifted or depressed by a crank 219. The support at its top carries a longitudinally 110 sliding frame 223, which may be moved bodily toward and from the shoe by a hand-wheel 225, adapted to be locked when the parts are in wiping position by a lock device 226. 115

The sliding frame 223 supports above it a transversely swinging carriage 228, upon which the wiping devices are carried. This carriage is movable transversely upon curved guides 229, which are in the form of arcs 120 struck about the apex of the heel wiper plate contour as a center.

By this arrangement one is permitted to adjust the jack to the required incline to co-operate, as before described, with the toe 125 wiping mechanism, during which the apex L' of the heel of the shoe remains substantially stationary on account of its proximity to the center D, about which the jack swings, (see Fig. 11). It is, therefore, merely nec- 130

essary to swing the heel wiper plates about their own apex to adapt them to any adjustment of the jack and shoe.

While this adjustment might be performed by hand and determined by eye, there is herein disclosed an automatic arrangement for determining or effecting the swinging adjustment of the carriage 228, according to the position of the jack. The carriage is shown provided with a depending stud or roller 230 engaging a guiding extension or tail, which is seen as extending rigidly from the right of the jack. This guiding extension is formed with side walls 232, between which is a groove engaged by the stud 230. The groove has a flaring entrance, so that, when the stud is retracted, it will readily find its position again in the groove.

When the sliding frame 223 and the wiping head are retracted, the stud 230 may stand to the right of the guiding extension. In this position the jack may be adjusted for changes in shoe style. Upon bringing the wiping head toward the shoe, the operator is relieved from the need of determining the position of the swinging carriage or the line of wiping action, since the engagement of the stud and guiding extension automatically determine that. Further, when the jack is thrown symmetrically across from one side to the other in changing from rights to lefts, and vice versa, the swinging carriage 228 is caused to correspondingly swing in the reverse direction. Thus, the action of the pedal in unclamping one shoe and clamping the next automatically determines or effects the position of the heel wiping head. This is important additionally because minimizing the difficulty of resetting the machine in changing over from rights to lefts, thus tending to render practical the plan of lasting the right and left shoes of a pair before lasting other pairs.

Above the swinging carriage 228 are opposite brackets 234 having trunnion bearings 235 at the top, between which are supported a longitudinally tilting shell 237, inside of which is contained a laterally tilting carriage 240. The wiper plates 270 and their actuating mechanism, including the operating handle 280, are all mounted on the carriage 240, and therefore partake of the lateral tilting movements of that carriage and the longitudinal tilting movements of the shell 237 and the swinging movements of the carriage 234. As described in said application No. 97,516, it is proposed that, when the jack is reversed in position, or when the carriage 234 is correspondingly reversed, one or both of these actions will effect the symmetrical reversal of the lateral tilt of the wiping plates and the carriage 240 supporting them. The details of the connections by which the operating handle

280 moves the wiper plates toward and from the shoe, and causes them at the same time to swing toward and from each other, are better shown and described in said application No. 97,516.

70

The operation of the above described lasting machine may be as follows: The shoe containing the last will first be engaged upon the heel rest, and then moved toward the left until snugly seated on the toe rest. 75 If there has been a change in the shoe style operated upon, the jack will be swung transversely to a slight degree until the shoe toe apex is brought into the longitudinal axis, or in alignment with the shoe heel apex. 80 During this setting of the jack the toe wiping mechanism will have been brought approximately into position, so that the wiper plates may serve as a gage in adjusting the shoe and jack. It will be understood that 85 during this adjustment the symmetrical stops for the jack will be properly readjusted to correspond with the new position of the jack. As soon as the operator is satisfied that the shoe is lying in the proper position the pedal 185 will be completely depressed, this applying the hold-down clamps to firmly press and hold the shoe upon the jack, and at the same time locking the heel rest against sliding and locking the jack 90 against swinging. The pedal is held locked in its depressed position, and the operator may remove his foot. The heel wiping head will now be slid toward the left up to the work. As explained, the angle of wiping action is automatically set to accord with the position of the shoe. After the proper adjustment of the longitudinal and lateral tilt of the wiper plates, the hand lever will be worked to perform the wiping operation. 100 The in-turned margins of the upper will be tacked or otherwise secured at the completion of the heel wiping operation. The heel wiping mechanism may be left in contact with the shoe for the toe wiping operation, although the described hold-down is sufficiently effective and rigid to dispense with the need of additional backing up of the work. The toe wiping mechanism will be set accurately as to the angle of wiping action, if not already set, and, after adjustment of the lateral and longitudinal tilt, the hand lever will be worked in conjunction with the lifting pedal to perform the wiping 110 in the usual manner. The wiped-in margins will be secured. Both wiping heads may be retracted from the shoe. The hold-down pedal will now be unlocked and allowed to rise under the influence of its spring. This causes the hold-down hooks to lift and separate, so that the shoe may be retracted. Also the lifting of the pedal symmetrically reverses the jack from one incline to the reverse, the laterally tilting wedge cam having 115 been reversed in position upon the previous 120

125

130

downward movement of the pedal. The shoe is now removed and its mate inserted. The jack having been already set, the hold-down clamps are applied by the depression of the 5 pedal, which, as before, becomes locked preparatory to the wiping operations. The depression of the pedal, as before, reverses the tilting wedge cam, so that, on the next rise of the pedal, the jack will be thrown 10 transversely across to resume its first position.

It will thus be seen that I have described a lasting machine and wiping mechanism embodying the novel principles of the present 15 invention and attaining the objects and advantages thereof; and further advantages in the described structure will be apparent to those skilled in the art. Many matters of mere design, arrangement, detail or sub-combination may be variously modified without departing from the underlying principles of the invention, and, therefore, there is no intention to limit the present invention to such features excepting in so far as the same are 20 recited in the appended claims.

What is claimed is:

1. In combination, a shoe holding jack comprising both heel and toe engaging members, said jack bodily swingable transversely 30 to bring the shoe toe apex into a given longitudinal line, and a toe wiping mechanism bodily swingable about a center located in said longitudinal line.

2. In combination, a shoe holding jack swingable transversely to bring the shoe toe 35 apex into a given longitudinal line, and a toe wiping mechanism bodily swingable about a center located in said longitudinal line and approximately at the toe wiper contour apex.

3. In combination, a shoe holding jack swingable transversely about a center approximately at the apex at the heel end of the shoe to bring the shoe toe apex into a 45 given longitudinal line, and a toe wiping mechanism bodily swingable about a center located in said longitudinal line and approximately at the toe wiper contour apex.

4. In combination, a shoe holding jack 50 swingable transversely about a center approximately at the apex at one end of the shoe to bring the shoe apex at the other end into a given longitudinal line, and a wiping mechanism at the latter end bodily swingable about a center located in said longitudinal line and approximately at the wiper contour apex, said wiping mechanism having 55 its direction of wiping action in line with said wiper contour apex, and being bodily invertible to reverse both the contour and the angle of action when changing from rights to lefts.

5. In combination, a shoe holding jack 60 swingable transversely approximately about the shoe heel apex to bring the shoe toe into

a predetermined line, and a heel wiping mechanism swingable about the heel wiper contour apex, to adjust its line of action to the shoe.

6. In combination, a shoe holding jack 70 swingable transversely approximately about the shoe heel apex to bring the shoe toe into a predetermined line, a heel wiping mechanism swingable about a vertical axis substantially at the heel wiper contour apex, to adjust its line of action to the shoe, and means to bodily move said heel wiping mechanism including said axis toward and from the shoe.

7. In combination, a shoe holding jack 80 swingable transversely approximately about the shoe heel apex to bring the shoe toe into a predetermined line, a heel wiping mechanism swingable about a vertical axis substantially at the heel wiper contour apex, 85 to adjust its line of action to the shoe, means to bodily move said heel wiping mechanism including said axis toward and from the shoe, and a toe wiping mechanism bodily swingable about an axis substantially at the 90 toe wiper contour apex.

8. In combination, a shoe holding jack swingable transversely approximately about the shoe heel apex to bring the shoe toe into a predetermined line, and a heel wiping 95 mechanism swingable about the heel wiper contour apex, to adjust its line of action to the shoe, said jack having means for determining or affecting the swinging adjustment of the heel wiping mechanism.

9. In combination, a shoe holding jack swingable transversely approximately about the shoe heel apex to bring the shoe toe into a predetermined line, and a heel wiping mechanism swingable about the heel wiper 100 contour apex, to adjust its line of action to the shoe, said jack having means for determining or effecting the swinging adjustment of the heel wiping mechanism, consisting of a swinging guide moved by the jack and a 105 co-operating member on the wiping mechanism.

10. In combination, a jack swingable about a center near one apex of the shoe sole, a wiping mechanism bodily shiftable longitudinally toward and from the jack to bring it into and from wiping position, said wiping mechanism being swingable about a center which is fixed against lateral movement for the purpose of adjusting the line of wiping action, and means whereby the swinging adjustment of the jack determines the adjustment of the line of wiping action.

11. In combination, a jack swingable about a center near one apex of the shoe sole, a wiping mechanism bodily shiftable longitudinally toward and from the jack to bring it into and from wiping position, said wiping mechanism being swingable about a center which is fixed against lateral movement, 125

but which accompanies said bodily longitudinal movement, and means whereby the swinging adjustment of the jack determines the adjustment of the line of wiping action.

5 12. In combination, a jack swingable symmetrically across the machine axis about a center located near one shoe sole apex for changing over the machine from rights to lefts, a wiping mechanism adjacent to the 10 end of the shoe about which the jack swings, said mechanism being bodily adjustable toward and from the jack and relatively swingable about an axis near the heel apex for symmetrically reversing the line of wiping action, and operative connections between the jack and wiping mechanism, whereby the reversal of one determines the reversed position of the other.

13. In combination, a jack swingable 20 symmetrically about a substantially vertical axis located near the shoe heel apex for changing over the machine from rights to lefts, heel wiping mechanism bodily adjustable toward the jack and relatively swingable about the apex of its wiping contour for symmetrically reversing the line of wiping action, and operative connections between the jack and wiping mechanism, whereby the reversal of the jack determines 30 the reversed position of the wiping mechanism.

14. In combination, a jack swingable about one end to bring both shoe apexes into a given longitudinal axis, and wiping 35 mechanisms for the respective ends of the shoe, both transversely swingable about centers located substantially at the contour apexes at the respective ends.

15. In combination, a jack swingable 40 about one end to bring both shoe apexes into a given longitudinal axis, and wiping mechanisms for the respective ends of the shoe, both transversely swingable about centers located substantially at the apexes of 45 wiper plate contour, and both bodily movable longitudinally so as to carry such centers of swinging toward and from the jack.

16. In combination, a toe wiping mechanism transversely swingable about an axis 50 substantially at the apex of its wiping contour to set its angle of wiping action to agree with the shoe toe center line, a shoe holding jack transversely swingable about an axis substantially at the apex of the heel of a shoe 55 held therein to bring the shoe toe apex into operative relation to the toe wiping mechanism, and a heel wiping mechanism transversely swingable about an axis substantially at the apex of its wiping contour to 60 set its angle of wiping action to agree with the shoe heel center line.

17. In combination, a jack having heel and toe rests and a hold-down, said jack being fitted to swing horizontally about a 65 vertical fulcrum substantially in line with

the apex of the shoe heel, whereby the shoe toe apex may be brought into longitudinal alinement with the heel, and heel and toe wiping mechanisms adapted to operate upon the shoe when so positioned.

18. In combination, a bodily shiftable shoe holding jack comprising both heel and toe engaging members, and mountings therefor comprising a fulcrum substantially at the shoe apex at one end, about which the jack may swing transversely to bring the shoe apex and the shoe engaging member at the other end to a given position relatively to a wiping mechanism and such wiping mechanism.

19. In combination, a bodily shiftable shoe holding jack comprising both heel and toe engaging members, and mountings therefor comprising a fulcrum substantially at the shoe apex at one end, about which the jack may swing transversely to bring the shoe apex and the shoe engaging member at the other end to a given position relatively to a wiping mechanism, and such wiping mechanism; said mountings being arranged to permit the jack to swing from an inclined position suitable for a right shoe to an oppositely inclined position suitable for a left shoe; and a stopping means for symmetrically limiting the swinging movement of the jack in either direction, the same having means for simultaneously symmetrically adjusting the stopping means.

20. In combination, a frame, a jack having a shoe-rest and a hold-down, a part or pedal for applying the hold-down to clamp a shoe on said shoe-rest, and releasable means for locking the hold-down in clamped position; said hold-down comprising opposite hooks fitted to approach and descend when applied to a shoe, a spring tending to pull the hooks together, and a single member for first lifting the hooks and then separating them against the spring's resistance.

21. In combination, a frame, a jack having a shoe-rest and a hold-down, said jack being swingable over said frame, a device to lock the jack against swinging, a part or pedal for applying the hold-down to clamp a shoe on said shoe-rest, and for applying 115 said jack locking device, and releasable means for locking the pedal in clamped position.

22. In combination, a frame, a jack having a shoe-rest and a hold-down, said shoe-rest being adjustable over said jack, a device to lock the shoe-rest against adjustment, a part or pedal for applying the hold-down to clamp a shoe on said shoe-rest, and for applying said locking device, and releasable 120 means for locking the pedal in clamped position.

23. In combination, a frame, a jack having a shoe-rest and a hold-down, mountings adapting the jack to be bodily shifted 130

transversely over the frame for changing the machine over from rights to lefts and vice versa, a part or pedal operable at will, and connections whereby the pedal operation 5 shifts the jack.

24. In combination, a frame, a jack having a shoe-rest and a hold-down, mountings adapting the jack to be bodily shifted transversely over the frame for changing the 10 machine over from rights to lefts and vice versa, a part or pedal operable at will for applying the hold-down to clamp a shoe on the shoe-rest, and connections whereby the pedal operation shifts the jack.

15 25. In combination, a frame, a jack having a shoe-rest and a hold-down, mountings adapting the jack to be bodily shifted transversely over the frame for changing the machine over from rights to lefts and vice 20 versa, a part or pedal operable at will for applying the hold-down to clamp a shoe on the shoe-rest, and connections whereby the pedal operation shifts the jack; the parts being constructed and arranged so that the down 25 movement of the pedal applies and locks the hold-down, while its upward movement shifts the jack.

26. In combination, a frame, a jack having a shoe-rest and a hold-down, mountings 30 adapting the jack to be bodily shifted transversely over the frame for changing the machine over from rights to lefts and vice versa, a part or pedal operable at will for applying the hold-down to clamp a shoe on 35 the shoe-rest, and connections whereby the pedal operation shifts the jack, comprising a reversible cam and stud device.

27. In combination, a frame, a jack having a shoe-rest and a hold-down, mountings 40 adapting the jack to be bodily shifted transversely over the frame for changing the machine over from rights to lefts and vice versa, a part or pedal operable at will for applying the hold-down to clamp a shoe on 45 the shoe-rest, connections whereby the pedal operation shifts the jack, comprising a reversible cam and stud device, and means for reversing the same at suitable times.

28. In combination, a frame, a jack having a 50 shoe-rest and a hold-down, mountings adapting the jack to be bodily shifted transversely over the frame for changing the machine over from rights to lefts and vice versa, a part or pedal operable at will for applying the hold-down to clamp a shoe on the shoe-rest, and connections whereby the pedal operation shifts the jack, comprising a reversible cam and stud device; the parts being constructed and arranged so that the down movement of 55 the pedal applies and locks the hold-down and reverses said cam and stud device, while its upward movement shifts the jack.

29. In combination, a frame, a jack having a shoe-rest and a hold-down, mountings

adapting the jack to be bodily shifted transversely over the frame for changing the machine over from rights to lefts and vice versa, a part or pedal operable at will for applying the hold-down to clamp a shoe on the shoe-rest, and connections whereby the 65 70 75 pedal operation shifts the jack, comprising a reversible cam and stud device having means for adjusting the extent of its action.

30. In combination, a frame, a jack having a shoe-rest and a hold-down, mountings adapting the jack to be bodily shifted transversely over the frame for changing the machine over from rights to lefts and vice versa, a part or pedal operable at will for applying the hold-down to clamp a shoe on 80 the shoe-rest, and connections whereby the 85 pedal operation shifts the jack, comprising a reversible cam and stud device having means for adjusting the extent of its action; and symmetrical limiting stops for the jack adapted to be symmetrically adjusted to correspond with the cam and stud adjustment.

31. In combination, a wiper device, an actuating carrier therefor operable along a line of action inclined to a given axis, a carriage supporting the carrier, and means for revolubly inverting the carriage about the said axis, whereby the angle of action is symmetrically reversed upon inversion, and a jack for holding a shoe swingably about 90 an axis near the tip of its heel.

32. In combination, a member or shell revoluble about a longitudinal axis for inverting the following mechanism carried thereby, namely, a carriage supported by the 100 member and swingingly adjustable therein, an actuating carrier movable on said carriage, and a wiper device on said carrier, said wiper device having the apex of its contour at the center of swinging of said 105 carriage, and a jack for holding a shoe swingably about an axis near the tip of its heel.

33. In combination, a toe wiping mechanism transversely swingable about an axis 110 substantially at the apex of its wiping contour to set its line of wiping action to agree with the shoe toe center line, a shoe holding jack transversely swingable about an axis substantially at the apex of the heel of a 115 shoe held therein to bring the shoe toe apex into operative relation to the toe wiping mechanism, and a heel wiping mechanism transversely swingable about an axis substantially at the apex of its wiping contour 120 to set its line of wiping action to agree with the shoe heel center line.

34. In combination, a toe wiping mechanism transversely swingable about an axis substantially at the apex of its wiping contour to set its line of wiping action to agree 125 with the shoe toe center line, a shoe holding jack transversely swingable about an axis

substantially at the apex of the heel of a shoe held therein to bring the shoe to apex into operative relation to the toe wiping mechanism, and a heel wiping mechanism trans-
5 versely swingable about an axis substantially at the apex of its wiping contour to set its line of wiping action to agree with the shoe heel center line; and means whereby the

swinging of the jack determines the angle of swing of the heel wiping mechanism. 10

In testimony whereof, I have affixed my signature hereto.
